US00D758861S

(12) United States Design Patent
Heidl et al.

(10) Patent No.: US D758,861 S
(b4) Date of Patent: * Jun. 14, 2016

(54) PRODUCT PACKAGE

(71) Applicant: National Concessions Group Inc.,
Denver, CO (US)

(72) Inventors: Jeremy Heidl, Denver, CO (US); Gary Ross, Fort Collins, CO (US); Ralph Morgan, Evergreen, CO (US); Blake St. Clair, Denver, CO (US); Gentlehart Acres, Denver, CO (US)

(73) Assignee: National Concessions Group Inc.,
Denver, CO (US)

() Term: 14 Years

(21) Appl. No.: 29/508,197

(22) Filed: Nov. 4, 2014

(51) LOC (10) Cl. 09-03

(52) U.S. Cl. USPC D9/457

(58) Field of Classification Search

USPC D6/466; D9/414–416, 418, 421, D9/423–426, 430, 432–438, 440, 443–445, D9/447, 449, 455–457, 499, 735, 739; 206/349, 459.5, 461, 484, 532; 211/70.6; 248/174

CPC B65D 73/0064; B65D 73/0021
See application file for complete search history.

(74) Attorney, Agent, or Firm — Sheridan Ross P.C.

(57) CLAIM

The ornamental design for product package, as shown and described.

DESCRIPTION

FIG. 1 is a front perspective view of the product package;

FIG. 2 is a front elevation view thereof;

FIG. 3 is a right elevation view thereof;

FIG. 4 is a left elevation view thereof;

FIG. 5 is a rear elevation view thereof;

FIG. 6 is a top plan view thereof; and,

FIG. 7 is a bottom plan view thereof.

The broken lines showing the product package are included for the purpose of illustrating environment and form no part of the claimed design.

1 Claim, 4 Drawing Sheets
